ILLUMINATED SIGN

Raymond Nauth, Buffalo, N. Y., assignor, by
mesne assignments, to Flexlume Corporation,
Buffalo, N. Y., a corporation of New York

Application January 30, 1935, Serial No. 4,103

8 Claims. (Cl. 40—130)

This invention relates to illuminated signs, and it has particular reference to the provision of a sign character of more or less translucent material, with which is combined one or more luminous tubes, the spectral characteristics of which are so related as to produce an attractive color effect.

One of the objects of the invention is to obtain an association of a luminous or "Geissler" tube with a translucent sign character whereby the light of the tube will be transmitted, reflected, or refracted in the character in such manner as to produce a soft, but attractive color effect. Another object of the invention is to so associate such tubes and characters as to produce a multi-colored letter, such, for example, as one having a red color on one part, and a blue color in another, with the two colors merging smoothly into each other.

Preliminary to a description of suitable ways in which these and other objects and advantages of the invention may be obtained in practice, it may be noted that, heretofore, it has been proposed to make sign characters of translucent material, and to illuminate the same by ordinary electric lights from the rear or concealed side thereof, thus producing a luminous sign. It has also been proposed to make sign characters of luminous tubes, which are sometimes generically referred to as "neon" tubes, although neon tubes are really but one form of such sources of illumination. It has also been proposed to dispose such luminous tubes in a recessed letter, so that the light of the luminous tube could be reflected from the sign character, and, in daytime, the letter itself could serve as the sign.

While these various proposals have found some place in the arts, it has long been recognized that none of them was entirely satisfactory. Essentially, one function of a sign is to attract attention, and a sign which gives a dull uniform color is inherently ineffective in arresting the attention of the observer as much as is desired.

Accordingly, the present invention contemplates a sign in which beautiful and attractive color effects may be obtained, so that the display of the sign will be noticed by any observer, whose attention is primarily attracted by its color effect. One means of securing the desired results is illustrated in the accompanying drawing, wherein:

Fig. 1 is a plan view of a portion of a sign, showing a character including the principles of the present invention;

Fig. 2 is a section on the line 2—2 of Fig. 1; and

Fig. 3 is an enlarged fragmentary view of the section shown in Fig. 2.

The numeral 10 designates the front end or mounting member of a sign frame, which may be formed with top and bottom walls 11 and 12, and a rear wall (not shown) similar to the face 10, when a double faced sign is desired. The face 10 receives a suitable number of sign characters such as the letter E shown in Fig. 1. As best shown in Fig. 3, the character is formed with a marginal portion defined by a pair of outstanding ribs 13 and 14, which are joined at their outermost extremities 15, but which are spaced at their base 16. The innermost ribs 14 are connected at their bases by a web 17 and the entire sign character is made of a material which will transmit light but, as the same time, will subject the transmitted light to considerable diffusion. Such materials may be called, generally, translucent materials, although clear glass having different colors in different portions thereof may be used in some instances.

The mounting member 10 may be cut away to follow the outline of the character, but it is preferred to have the face 10 substantially continuous and to place the character thereon in abutting relationship, and to secure the parts as hereinafter more fully described. When using the sign as illustrated, it is also advantageous in procuring some of the desired color effects to interpose a base plate 18, also formed of translucent material, between the base of the character and the mounting panel 10.

It will be understood that the material of which the character is formed is capable of reflecting, refracting, and transmitting light, so that all parts thereof will appear colored when properly illuminated. If desired, the ribs 13 and 14 may be of different colors and hence have different spectral characteristics. Similarly, the web 17 may have a different spectral characteristic from that of the ribs, and the base plate 18 may also have the same or a different color. Such variation in the color of the character itself permits the development of a multi-colored sign when using a monochromatic light. Or, since the elements of the character transmit light, two different illuminating colors may be employed, thereby producing a multi-colored and illuminated sign.

The source of illumination consists of a luminous tube disposed within the confines of the letter in such fashion that the emitted light will be reflected from or diffused through the character itself. Thus, the invention provides a luminous

tube 21 disposed between the innermost ribs 14 and above the web 17 so that the light of the tube will be reflected in part and transmitted in part by the ribs 14. It will at once be apparent that if 5 the opposite surfaces of the rib 14 have different color characteristics, then the illuminated sign will stand out in two colors, together with various merging tints and shades thereof.

The tube 21, which follows substantially the entire length of the character, has its extremities turned inwardly to pass through apertures 22 formed in the web 17 and through aligned apertures (not shown) formed in the mounting member 10. As shown best in Fig. 2, these extremities 10 constitute electrode receiving portions 23 disposed in cups 24 and connected to a source of energizing current through wires 25. As the details of the electrical system form no part of this invention, it is deemed unnecessary to describe or illustrate 15 them further.

Disposed in the space between the ribs 13 and 14 and adjacent the base 16 thereof, is a second luminous tube 27, which, like the tube 21, follows the outline of the character. This tube may have 20 the same or a different color characteristic from the tube 21, depending upon the effect sought. Thus, it may be assumed that the character is formed of a white glass composition and the tube 21 is a neon tube whose color characteristic is 25 red. It may also be assumed that the tube 27 has a blue characteristic. In such a sign, the light from the red tube will be reflected in part from the surfaces 14 and transmitted in part to the 30 space between the ribs 13 and 14. At the same time, the light from the tube 27 will be transmitted in part through the ribs 13 and 14, and hence it will be understood that while the outer edge of the sign has a predominantly blue color, the inner portions are predominantly red, and 35 these two colors will merge into varying shades and hues, depending upon the composition of the respective exciting wave lengths at any other point.

It will also be understood that either the tube 40 27 or the tube 21 may be dispensed with while still obtaining a beautiful soft light, whose characteristic will depend on the specific characteristics of the illuminating source and the material illuminated.

In order to prevent a glare by direct transmission to the eye from the tube 21, it is advantageous to frost the surface of the tube 21, so that a diffused light is transmitted thereby.

The entire unit may be effectively mounted by 45 means of the mounting member best shown in Fig. 3. This member consists of a plate 31 formed with apertures to receive threaded bolts 32 which pass through the web 17, base plate 18, and mounting member 10. By providing a suitable 50 number of such brackets, as indicated in Fig. 1, the character is held tightly against the frame and no additional means need be provided to secure the luminous tube 21, which is pinched between the base and the inner surfaces of the ribs 13 and 14. The bracket 31 is also provided with a cup 55 33 in which is disposed an insulating post 34 formed with a saddle 35 at its outermost end. The tube 21 rests in the saddle and it is secured thereto by means of a tie wire 36. It will thus be seen that all parts of the sign may be readily and securely assembled in the desired relationship.

While the invention has been described with respect to only certain embodiments of its principles, it will be understood that a wide variety of 70 combinations and effects can be obtained without

departure from the foregoing teachings. It is therefore desired that the invention should be construed in the light of the following claims.

I claim:

1. A sign adapted for day and night display 5 comprising a sign character formed with a sharply upstanding marginal portion and sharply upstanding border portion disposed within and following the contour of said marginal portion, said character having a base, said marginal portion 10 and border portion constituting a pair of ribs projecting outwardly from said base and being formed of light transmitting and refracting material, said ribs being spaced at said base and being conjoined at their outer ends whereby said marginal portion and border portion merge into each other, and a luminous tube disposed between said ribs and adjacent the base, said tube being practically in contact with said ribs, whereby, during the daytime said sign character presents 15 a visible sign and during night display and upon illumination of said tube said ribs receive and transmit over substantially the entire area thereof the light emitted by said tube.

2. In a luminous sign, a sign character formed 20 of light-transmitting material having its marginal portion defined by a pair of conjoined outstanding ribs spaced at the base of the character, a luminous tube disposed in the base between said ribs, and a second luminous tube disposed between 25 said ribs and within said marginal portion.

3. In a luminous sign, a sign character formed 30 of light-transmitting material, said character having a marginal portion defined by a pair of conjoined outstanding ribs spaced at the base of the character, a web connecting said ribs lying within said marginal portion, and luminous tubes 35 disposed both between said conjoined ribs and above said web.

4. A sign adapted for day and night display 40 comprising a sign character formed with an upstanding marginal portion and an upstanding border portion disposed within and following the contour of said marginal portion, said character having a base, said marginal portion and said 45 border portion constituting a pair of ribs projecting outwardly from said base and being formed of light transmitting and refracting material, said ribs being spaced at said base, the border portion of said character being also spaced on 50 opposite sides of said character, a web connecting the said spaced sides, and a luminous tube disposed above said web and between the said sides, said tube being of less diameter than the height of said upstanding ribs and being spaced from said 55 web but lying substantially wholly between said web and the outermost extremities of said ribs, whereby said character is effective for daytime display and a major portion of the illumination from said tube during night display is received 60 on the adjacent surfaces of said border portion.

5. In a luminous sign, a sign character formed 65 of light-transmitting material, said character having a marginal portion formed by a pair of spaced outstanding ribs and a web connecting the innermost of said ribs defining said marginal portion, a luminous tube disposed in the space between said ribs, and a second luminous tube disposed between the innermost ribs and above said web, the characteristic colors of said tubes being 70 different.

6. In a luminous sign, a sign character having 75 a marginal portion of translucent material defined by a pair of outstanding ribs spaced at the base of said portion, the spectral characteristics of 75

said material being different in the said ribs, and a luminous tube disposed at the base of said character between said ribs, whereby light transmitted by said tube through said ribs will impart to the 5 character a multi-colored effect.

7. In a luminous sign, a sign character having a web base and an outstanding marginal portion contiguous with said base, said web base being formed of translucent material, a luminous tube 10 disposed within said marginal portion and above said web, said tube having a translucent surface to diffuse the light passing therethrough.

8. In a luminous sign, a mounting member, a sign character disposed on said mounting member, 15 said character being formed of translucent mate-

rial and having a marginal portion defined by a pair of outstanding ribs spaced adjacent the mounting member, the innermost of said ribs being connected by a web, a base plate of translucent material interposed between the web and ends of the outermost ribs and said mounting member, a luminous tube disposed in the space between said ribs, a second luminous tube disposed between the innermost ribs and above said web, and securing means for said last named tube, said securing means passing through said web, base plate, and mounting member to hold all the parts in assembled relation. 5 10
